COMBINED POCKET MIRROR AND FLASHLIGHT

Sidney Schwartz, New York, N. Y.

Application May 2, 1955, Serial No. 35,779

Term of patent 14 years

(Cl. D48—24)

Fig. 1 is a perspective view showing the top, front and one side of a combined pocket mirror and flashlight embodying my new design, with the mirror in open extended position.

Fig. 2 is a perspective view showing the bottom, rear and other side of my design shown in Fig. 1, and

Fig. 3 is a side elevational view of the combined pocket mirror and flashlight shown in Figs. 1 and 2 reduced to scale but with the mirror in closed position.

I claim:

The ornamental design for a combined pocket mirror and flashlight, as shown.
